UNITED STATES PATENT OFFICE.

CHARLES H. KNOWLES, OF FAIRFIELD, MAINE.

WINDOW-SCREEN.

No. 875,826.

Specification of Letters Patent.

Patented Jan. 7, 1908.

Application filed July 13, 1906, Serial No. 326,104. Renewed November 21, 1907. Serial No. 403,190.

To all whom it may concern:

Be it known that I, CHARLES H. KNOWLES, a citizen of the United States of America, and resident of Fairfield, Maine, have invented certain new and useful Improvements in Window-Screens, of which the following is a specification.

My invention relates to a window screen such as are used for excluding flies, and other insects from houses and it relates particularly to a screen adapted to be inserted in place from inside the window and to be applied without the use of strips or guides. Screens of this character are generally made with grooves in the side bars, these grooves engaging vertical guides or strips which are secured to the casing just outside the upper sash. These screens are generally made to order to fit particularly windows because there is little latitude for variation as they are generally constructed, to allow for differences in the casing of windows supposed to be of the same size.

The object of my invention is to make a screen which will have sufficient lateral expansibility to fit all windows having the same sized glass, which may be applied quickly and easily from the inside and without the necessity of nailing strips to the casing and which may be raised and lowered sufficiently for all practical purposes.

In carrying out these objects I make a screen in the usual way with end and side bars, one of the side bars having co-operating with it a laterally movable extension bar forced outward by springs and held to the side bar with suitable guides. The screen is held in place immediately outside of the upper sash against outward displacement by holding plates which are applied to the inner faces of the side bars and extend outward into the groove occupied by the upper sash, one of these holding plates being secured to the extension bar and being capable of being retracted to allow the screen to be placed in position from the inside of the window. As I construct the screen, it is held against inward displacement or liability to be pushed inward by lateral projections on the outer face preferably at or near the lower ends of the side bars, these projections bearing against the outer face of the window casing which is generally of uniform thickness in all houses namely about $\frac{1}{8}$ inches or a trifle thinner than the thickness of the screen. This fact enables me to make use of

this construction and to avoid the necessity of using special strips.

I illustrate my invention by means of the accompanying drawing in which:—

Figure 1 is an elevation of the screen looking from the inside, Fig. 2 is a section on yy of Fig. 1 and Fig. 3 is a section on xx of Fig. 1.

The screen is made up in the usual manner with the end bars b and b' and side bars d and c . As here shown, one of the side bars is rabbeted out at its inner face and in the rabbet is placed the flat extension bar e which acts to take up the variations in the different windows fitted. The extension bar e is so mounted that it has a lateral motion with respect to the side bar c . As here shown, the connection is made by pins e' in the inner edge of the extension bar which pass through and slide in openings through the bar c . Springs e'' are provided between the inner edge of the bar e and the rabbeted portion of the bar c for forcing the bar e outward against the casing of the window. The amount of play of bar e is such that when at its inner position the screen will just pass through the narrowest window that would be found with the width of glass which the screen was intended to be used for and when at its outer position the edge of the bar e would be something more than wide enough to reach the casing.

The screen is held in place in the window against outward displacement by holding plates which are secured to the inner face of the side bars preferably about in the center and which project out far enough to catch the shoulder formed by the outer portion of the groove occupied by the upper sash.

On one side is the stationary plate d' fixed to the side bar d with screws and having preferably on its inner end a handle by which the screen is handled, the outer end of the plate projecting beyond the edge of the bar. The holding plate F on the opposite bar is slidably held both with relation to the extension bar e and the side bar C and it performs the function of retracting the extension bar and holding the screen in place. As here shown, it is connected with the bar e by means of a screw f' passing through slots f so that when retracted it first draws back the outer end of the plate F thus freeing the screen and allowing it to be swung inward and upon being further retracted it draws in the extension bar thus releasing the screen from the friction caused by the outward

pressure of the bar against the casing. The plate F is as here shown, provided with means whereby it may be clamped to the bar C to hold the plate in its outer position so 5 that it cannot be accidentally withdrawn. For this purpose as here shown, I provide a thumb screw f^3 engaging an opening in the side bar in connection with a slot f^2 in the holding plate. On the inner end of the plate 10 f is a handle to be used in connection with the handle of plate d' for manipulating the plate and also for handling the screen. The screen is held against the inward displacement or against any force tending to press it 15 inward at the top by resting against the outside of the lower rail of the upper sash and as to the lower portion of the screen by lateral projections n and n' on the outer face of the side bars, preferably at their lower ends. 20 These projections may be small metal plates projecting beyond the edge of screen and rest against or in proximity to the outer face of the window casing as above stated.

From what has been said the operation 25 and advantages of my screen are apparent. When it is desired to put in the screen, the thumb screw f^3 is loosened, the bar e and the plate F drawn into their inner positions in which condition the screen is passed through 30 the window to the outside by tilting it and the side of the screen carrying the bar d may be inserted at an angle the bar d resting against the casing just outside the groove of the upper sash the end of the plate d' resting 35 against the outer edge of the groove, and projection n' against the outer face of the window casing. The bar C can now be swung inward clearing the casing until it reaches the same position as bar d and with the 40 upper bar b brought to rest against the outside of the lower rail of the upper sash and projection n coming against the outer face of the casing. The lower bar of the screen is beveled to rest on the inclined sill 45 of the window. Having inserted the screen, the plate F is released and the bar e immediately springs out and presses against the casing i and by pushing out the plate F its end projects into the groove j of the upper 50 sash. The plate F is then locked in place by the thumb screw f^3 . It will be seen that when held in this position the screen can be raised by sliding it upward until the plates F and d' come against the lower rail of the 55 upper sash. It is held firmly against both inward and outward displacement and forms tight joints with the casing and upper sash. A screen made in this manner with allowance made for variation in the widths 60 of windows which use the same width of glass may be made and kept in stock by hardware and other stores and be inserted by the purchaser without any fixtures being attached to the house.

65 The holding plate F may if desired be im-

movably fixed to the extension bar e with its outer end projecting out beyond the edge of the bar, by tightening the thumb screw f^3 , as shown in Fig. 1, the play of the bar laterally being sufficient to allow the same to be drawn 70 in by the casing when the bar is retracted. This arrangement however, is less desirable than that described since it would require a larger amount of play for the bar e to cover the same variations in different sizes of 75 window casing.

I claim:

1. The herein described window screen having end bars and side bars, a lateral extension bar slidably connected with one of 80 the side bars, a holding plate adjustably mounted on the inner face of said extension bar to extend beyond the outer edge of the extension bar, and a holding plate on the inner surface of the opposite side bar extending beyond the outer edge of said side bar.

2. The herein described window screen having end bars and side bars, a lateral extension bar slidably connected with one of 90 the side bars, a holding plate adjustably mounted on the inner face of said bar to extend beyond the outer edge of the extension bar, means for clamping the holding plate to the side bar, and a holding plate on the inner surface of the opposite side bar extending beyond the outer edge of said side bar.

3. The herein described window screen having end bars and side bars, a lateral extension bar slidably connected with one of 100 the side bars, springs for holding said extension bar in its outer position, a holding plate mounted on the extension bar to extend beyond the outer edge thereof, means for clamping said holding plate to the side bar, and a 105 holding plate on the opposite side bar extending beyond the outer edge of said bar.

4. The herein described window screen having end bars and side bars, a lateral extension bar slidably connected with one of 110 the side bars, springs for holding said extension bar in its outer position, a holding plate provided with horizontal slots, screws passing through said slots for adjustably securing the holding plate to the inner surface of the 115 extension bar, said holding plate being adapted to have its outer end project beyond the outer edge of the extension bar, and a holding plate on the opposite side bar.

5. The herein described window screen 120 having end bars and side bars, one of said side bars being rabbeted out on its inner face, a lateral extension bar held in said rabbet, pins in the inner edge of said extension bar and holes in the side bar for the passage of 125 said pins, springs between the inner edge of the extension bar and the surface of the side bar for forcing the extension bar outward, a holding plate having horizontal slots, screws passing through one or more of said slots for 130

adjustably securing said plate to the extension bar, a thumb screw passing through one of said slots for securing the plate to the side bar and a holding plate on the opposite side bar 5 extending beyond the outer edge thereof.

6. The herein described window screen having end bars and side bars, a lateral extension bar slidably connected with one of the side bars, springs for holding said extension bar in its outer position, a holding plate provided with horizontal slots, screws passing through some of the slots for adjustably securing the holding plate to the inner surface of the extension bar, said holding plate being 10 adapted to have its outer end project beyond the outer edge of the extension bar, a thumb screw passing through one of the slots in the holding plate to clamp the holding plate to one of the side bars, and a holding plate on 15 the opposite side bar.

7. The herein described window screen having end bars and side bars, a lateral extension bar slidably connected with one of the side bars, a holding plate adjustably mounted on the inner face of said extension bar to extend beyond the outer edge of the extension bar, a holding plate on the inner surface of the opposite side bar extending beyond the outer edge of said side bar, and lateral extensions on the outer face of the lower portion of the screen to bear against the outer surface of the window casing.

8. The herein described window screen

having end bars and side bars, a lateral extension bar slidably connected with one of the side bars, a holding plate adjustably mounted on the inner face of said extension bar to extend beyond the outer edge of the extension bar, and having a handle formed on its inner end, and a holding plate on the inner surface of the opposite side bar extending beyond the outer edge of said side bar.

9. In combination with a window casing, including beads arranged to form sash guides, and a sash mounted in the guides, of a window screen having end bars and side bars, two oppositely disposed holding plates mounted on the inner surface of the side bars intermediate the ends thereof, one of said plates being movably mounted, two oppositely disposed holding plates secured to the outer surfaces of the side bars at their lower ends, said screen being associated with the window casing so that its inner surface is flush with the outer surface of the upper sash, the holding plates projecting beyond the side bars of the screen and engaging the side surfaces of the opposite outer beads of the casing.

In witness whereof I have hereunto set my hand this 30th day of June, 1906.

CHARLES H. KNOWLES.
